UNITED STATES PATENT OFFICE.

HERMAN E. KUHNER, OF OXFORD, MARYLAND; ROSE L. KUHNER EXECUTRIX OF
SAID HERMAN E. KUHNER, DECEASED.

CRANE.

1,116,713.

Specification of Letters Patent.

Patented Nov. 10, 1914.

Application filed July 15, 1913. Serial No. 779,195.

To all whom it may concern:

Be it known that I, HERMAN E. KUHNER, a citizen of the United States, residing at Oxford, in the county of Talbot and State 5 of Maryland, have invented certain new and useful Improvements in Cranes; and I do hereby declare the following to be a full, clear, and exact description of the invention, such as will enable others skilled in 10 the art to which it appertains to make and use the same.

This invention relates to portable cranes specially adapted for use in workshops and garages in connection with motor cars; and 15 it consists in the novel construction and combination of the parts hereinafter fully described and claimed whereby the load can be lifted from two points simultaneously or from a single point.

20 In the drawings, Figure 1 is a front view of a crane constructed according to this invention. Fig. 2 is an end view of the crane. Fig. 3 is a longitudinal section through the winding mechanism, taken on 25 the line $\alpha-\alpha$ in Fig. 1, and drawn to a larger scale. Fig. 4 is a plan view of the catch.

The crane is mounted on a wheeled truck and has an arch-shaped main frame adapted 30 to extend over a motor car. The hoisting mechanism is arranged at one side of the frame, and two barrels and two lifting cords or cables are provided. These lifting cords are conducted over guide sheaves on 35 the frame so that the car can be lifted at each side simultaneously, or so that its engine can be lifted out by one of the cords at the middle of the frame.

The main frame 2 of the crane is arch-shaped in form and consists of angle-shaped 40 metallic bars arranged side by side and suitably braced together. These bars may each be formed of a single piece, or they may have curved brackets 3 for connecting their 45 horizontal and vertical portions and for bracing them together. The main frame 2 is mounted on a truck or trucks 4 having suitable wheels or casters 5, so that the crane may be moved about the workshop or garage 50 with facility. The hoisting mechanism 6 is secured to the upright portion at one side of the main frame 2. Two hoisting cables, cords or chains 7 and 8 are provided, and are wound upon barrels 9 and 10 respectively. 55 These cords are passed over a guide

roller 12 journaled at about the middle of one of the curved brackets 3. One cord 7 is then passed over a guide sheave 14 journaled adjacent to the roller 12, and the other cord 8 is extended across the top of the frame 60 and is passed over a guide sheave 15 journaled in the other curved bracket 3. The sheaves are arranged so that the cords depend symmetrically from the top of the frame, and an additional guide sheave 16 65 is journaled at the middle part of the frame. This sheave 16 supports the horizontal portion of the cord 8, and enables the free end portion of the cord to be hung from the middle of the frame at will, as indicated in dotted lines, so that it can be used to lift the motor out of the car or for any similar purpose. The other cord 7 can also be supported in a similar manner so that both 70 cords can be used at once for lifting at the 75 middle part of the crane. The cords are preferably wire ropes or cables.

The two barrels 9 and 10 are arranged upon a single shaft 18 which is journaled in bearings 19 and 21 on a frame 20 which is 80 secured to one side of the main frame, and which also assists in bracing the vertical members of the main frame. The barrel 9 is secured on the shaft 18 by a key or pin 22, and the barrel 10 is free to revolve and to 85 slide longitudinally on the shaft 18. The barrels are provided on their adjacent ends with toothed clutch members 23 adapted to engage with each other, and a spring 24 is provided between the barrels for normally 90 holding the clutch members out of engagement with each other. A worm-wheel 25 is journaled loosely on the shaft 18 between the barrel 9 and the bearing 21. A pin 26 is provided and is arranged to slide in a 95 hole in the worm-wheel and to engage with a hole 27 in the barrel 9. This pin is slid in and out by hand. A hand-wheel 28 is secured on the shaft 18 outside the frame 20, for revolving the shaft to adjust the relative 100 lengths of the cords 7 and 8. The hub of the worm-wheel 25 runs in contact with one end of the bearing 21 and with one end of the barrel 9, and the hub of the hand-wheel 28 runs against the other end of the bearing 105 21, so that the shaft 18 and the worm-wheel cannot slide longitudinally. A worm 30 is secured on a shaft 31 journaled in suitable bearings on the frame 20, and a handle 32 or other suitable means for revolving the 110

shaft 31 is provided. The worm 30 gears constantly into the worm-wheel and sustains the load when lifted. A face-cam 34 is formed on or secured to the bearing 19, and 5 a lever 35 is pivoted on the shaft 18, between the bearing 19 and the barrel 10, and has a face-cam 36 formed on it which engages with the face-cam 34. When the lever 35 is moved in one direction, as shown in Fig. 3, 10 the barrel 10 is slid longitudinally toward the barrel 9 by the face-cams, so that the two clutch members engage with each other. A spring-actuated catch or latch 40 is provided for holding the two barrels locked 15 together. This catch 40 is pivoted to the frame 20 by a pin 41 and it has a curved end portion 42 and a notch 43. The lever is pressed against the curved part 42 until the notch is caused to engage with the lever, by 20 the spring 44. The catch is retracted by hand to release the lever, and when the lever is moved in the reverse direction the spring 44 slides the barrel 10 out of engagement with the barrel 8. When the barrels 25 are disengaged, the barrel 9 is released from the worm-wheel and is revolved by the hand-wheel to adjust the lengths of the free end portions of the two lifting cords to suit the load. When the two cords are attached 30 to the load, the barrels are locked together, and if necessary both can be revolved by the hand-wheel to take up the slack of the cords. The barrel 9 is then connected to the worm-wheel by the slideable pin, and the load is 35 raised and lowered by the worm and worm-wheel, both barrels being revolved simultaneously, and the load being raised from two points so that it is kept level.

What I claim is:

40 1. The combination, with a frame provided with bearings, and a non-slideable shaft journaled in the said bearings; of a non-slideable barrel secured on the said shaft, a

worm-wheel mounted loosely on the said shaft and arranged in contact with the inner 45 end of one of the said bearings and with one end of the said barrel, a disengageable catch for connecting the worm-wheel to the said barrel, a worm for revolving the worm-wheel, means for revolving the said shaft when the 50 worm-wheel is disconnected from the barrel, a slideable barrel journaled loosely on the said shaft, clutch-members on the adjacent ends of the two barrels, and means for moving the slideable barrel longitudinally to 55 place the clutch-members into and out of engagement with each other.

2. The combination, with a frame provided with bearings, and a non-slideable shaft journaled in the said bearings; of a 60 non-slideable barrel secured on the said shaft, a worm-wheel mounted loosely on the said shaft and arranged in contact with the inner end of one of the said bearings and with one end of the said barrel, a disengageable 65 catch for connecting the worm-wheel to the said barrel, a worm for revolving the worm-wheel, means for revolving the said shaft when the worm-wheel is disconnected from the barrel, a slideable barrel journaled loosely on the 70 said shaft, clutch-members on the adjacent ends of the two barrels, a spring arranged between the two barrels and normally holding the clutch-members apart, a face-cam secured to the other shaft bearing, and 75 a lever provided with a face-cam and pivoted on the shaft between the said face-cam and the slideable barrel and operating to place the clutch-members in engagement with each other.

In testimony whereof I have affixed my signature in the presence of two witnesses.

HERMAN E. KUHNER.
